ATTORNEY

UNITED STATES PATENT OFFICE

134,108

DESIGN FOR A DOORSTOP

Joseph Adler, Bronx, N. Y., assignor to Stanley
M. Musicante, New York, N. Y.

Application July 6, 1942, Serial No. 107,433

Term of patent 7 years

To all whom it may concern:

Be it known that I, Joseph Adler, a citizen of the United States, residing in Bronx, county of Bronx, and State of New York, have invented a new, original, and ornamental Design for a Doorstop, of which the following is a specification, reference being had to the accompanying drawing forming a part thereof.

Fig. 1 is a perspective view of a doorstop, showing my new design.

Fig. 2 is a side elevational view.

Fig. 3 is an end view.

I claim:

The ornamental design for a doorstop, as shown.

JOSEPH ADLER.
